OIL AND STEAM REGULATING VALVE

Sinius M. Hansen, Lynn, Mass.

Application July 25, 1934, Serial No. 736,867

1 Claim. (Cl. 137—153)

The present invention relates to improvements in fuel valves for the regulation of steam supply, and more especially for steam supply systems wherein there is an intermittent demand for high heat, as in garment pressing applications, restaurant heaters, etc. Heretofore, such devices have been regulated by valves which are in theory responsive to the pressure of the steam to cut down the fuel supply to the burner, thus indirectly providing a floating regulation of the supply of steam between predetermined limits of steam supply pressure and fuel supply pressure. In practice, however, the regulation obtained by such valves has not been satisfactory as the range of variations has been too wide, and the lack of more accurate regulation has been a potential fire-hazard. For example, in certain devices of the prior art designed to do the work required, it has been customary to provide a packing between the steam side and the fuel side of the valve. This packing has the disadvantage that it usually leaks and as a consequence, the regulation is destroyed and the results are deceptive to such a degree that the boiler may blow out. In some devices, also, the control of fuel to the burner is accomplished by means of a needle valve which cuts down the amount of fuel admitted to the burner by restricting the fuel passages. By my present invention I eliminate altogether the requirement for the use of a packing and, furthermore, the area of the fuel passages to the burner is always constant, the control of the opening and closing of the fuel valve being accomplished by a special provision of my invention to afford close regulation thereof in response to the variations in pressure of the steam supplied to a bellows or sylphon actuating device for controlling said fuel valve. Thus, the regulation involved is accurate and dependable; also, the structure is a far cheaper one to build from a manufacturing standpoint. My invention will be more clearly understood by referring more specifically to the accompanying specification and drawing in which Fig. 1 is a sectional elevation of my improved valve; Fig. 2 is a view of the steam inlet coupling flange; Fig. 3 is a partial sectional view on line A—A of Fig. 1; Fig. 4 is a partial section taken on line B—B of Fig. 1 showing the fuel passage around metering-pin adjustment, and Fig. 5 illustrates in partial section the steam actuated bellows or sylphon for controlling the regulation of the fuel supply in response to the pressure of the steam.

Referring more specifically to the various figures of the drawing 1, Fig. 1 represents the

valve casing in which is a sylphon or bellows 2 of suitable metal secured within the casing by means of the steam inlet flanged head 3, secured to the flanged head 2' by means of the gaskets 4 and coupling-bolts 5. A passage 4' admits steam from the boiler (not shown) to the inside of the sylphon or bellows 2. The inner end of this bellows is seated in what may be called a sylphon head 6 within the valve casing 1, a portion of the head being reduced in cross-sectional area to provide a chamber 7 to receive oil leakage around metering-pin 8 resting on the sylphon head 6 and held in contact with bellows 2 by spring 6'. The oil which leaks into chamber 7 has an outlet passage 9 into oil by-pass passage 10. Thus, by-passing of the leakage oil in chamber 7 prevents the building up of back pressure of said oil on the steam sylphon or bellows 2, which would otherwise destroy the regulation by the amount of this leakage and corresponding back pressure. For example, if the bellows 2 was set to operate at sixty pounds to open the fuel valve and there should be a leak of oil into chamber 7 sufficient to build up a back pressure on the bellows 2 equal to say, five pounds, then although the bellows 2 may be set to operate at sixty pounds to open fuel valve 16, the fuel valve 16 would not actually be opened until the steam pressure was sixty-five pounds.

In the right hand end of the main valve within the casing 1 is another chamber 11 closed by a valve-cap 12 screwed into the casing 1. The wall of the chamber 11 is screw-threaded to receive the valve-cap 12 and the pressure regulating nut 13. The latter is chambered to receive a spring 14 which abuts at one end against a flange 15 on a secondary valve 16 which controls the passage of the fuel to the inlet passages 17 and 18 to the burner (not shown). The fuel inlet passage 17 communicates with an oil chamber 19 and passage 20 leading to by-pass 10 which by-passes oil back to the oil supply tank. Valve 16 is provided with an adjusting-screw 21 to control the pressure on the sylphon or bellows 2 for regulating the steam pressure required to open fuel valve 16 against the action of spring 14. The fuel valve 16 in turn may be regulated by screw 13. In order to regulate screw 21, cap-screw 12 and screw 13 are first removed and after screw 21 is regulated, screw 13 and screw 12 are replaced. In order to regulate screw 13 it is only necessary to remove capscrew 12. The metering-pin 8 is guided in a suitable bearing in the casing 1, and when the steam pressure rises to the predetermined amount to open valve 16 the pin 8

then abuts against the end of adjusting screw 21 forcing valve 16 open.

The operation of my invention is as follows: Assuming that it is desired to set the fuel valve 16 to operate at twenty-five pounds oil pressure when the steam pressure is sixty pounds. Cap-screw 12 is removed as is also regulating nut 13, and screw 21 is adjusted so that metering-pin 8 will abut against its left hand end when the steam pressure is sixty pounds, thus opening fuel valve 16. If it is desired to adjust the pressure of spring 14 against flange 15, regulating nut 13 is again replaced and adjusted to control the pressure of said spring to the predetermined amount. Cap screw 12 is subsequently replaced. There is now a pressure of twenty-five pounds on the oil from the fuel supply tank, the predetermined pressure of oil for operating the burner and just below sixty pounds steam pressure valve 16 is open. Should the steam pressure rise to sixty pounds or above, metering-pin 8 is actuated by bellows 2 to push on the end of screw 21 and open valve 16, thus by-passing oil into by-pass passage 20 and by-pass passage 10 whereby it returns to the oil supply tank. Thus, when the pressure of the oil tends to exceed twenty-five pounds or that pressure for which it has been set to operate, valve 16 opens and permits some of the oil to be returned to the oil supply tank. Thus, a regulating valve is provided whereby the relation of steam and oil pressures may be definitely controlled in a relatively simple, positive and inexpensive manner. If a packing around metering-pin 8 was depended upon to seal off the oil from chamber 11 or from inside nut 13, oil might leak into chamber 7 and build up a back pressure on bellows 2, but because of the fact that I allow oil to leak around metering-pin 8 into chamber 7, and prevent sufficient oil to be by-passed through

equalizing passage 9 into by-pass 10, no packing is necessary and no back pressure of oil has to be contended with.

In accordance with the provisions of the patent statutes, while I have described the principle of operation of my invention in a specific manner, it is to be understood that I do not limit my invention thereto since other modifications thereof may be made by those skilled in the art without departing from the spirit and scope of my invention.

What I claim and desire to secure by Letters Patent of the United States is:

A regulating valve for steam boilers supplied with oil fuel comprising a secondary valve responsive to oil pressure, a bellows, an inlet passage admitting steam within the bellows, a head for receiving the inner end of the bellows, an adjusting screw in the secondary fuel valve, a metering-pin resting on the bellows receiving head and in line with one end of the adjusting screw in the fuel valve, a casing for the valve enclosing a chamber within the casing for leakage oil around the bellows receiving head, a spring around said head, and a second spring around the fuel valve for adjusting the pressure on the latter, an adjusting nut for regulating the pressure on said spring, an oil chamber around the fuel valve, a removable cap screw for affording access to the adjusting devices adjacent the secondary valve, a by-pass passage for returning oil from the fuel valve chamber to an oil supply tank, an inlet passage to an oil burner connecting with said latter chamber when the fuel valve is open, and an equalizing passage connecting the leakage oil chamber around the steam pressure responsive device with the by-pass passage whereby back pressure of oil on the bellows is avoided.
